UNITED STATES PATENT OFFICE.

FREDERICK L. ANDERSON, OF HAVERHILL, MASSACHUSETTS, ASSIGNOR TO UNITED SHOE MACHINERY COMPANY, OF PATERSON, NEW JERSEY, A CORPORATION OF NEW JERSEY.

PIECED-STAY-JOINING MACHINE.

1,148,736.

Specification of Letters Patent. Patented Aug. 3, 1915.

Application filed January 25, 1910, Serial No. 539,999. Renewed November 20, 1911. Serial No. 661,420.

To all whom it may concern:

Be it known that I, FREDERICK L. ANDERSON, of Haverhill, in the county of Essex and State of Massachusetts, have invented 5 an Improvement in Pieced-Stay-Joining Machines, of which the following is a specification.

This invention relates to certain improvements in machines for connecting the portions of a pieced stay, and, more particularly, to certain improvements on the machine shown in my prior Patent No. 913,934, dated March 2, 1909, in which means are provided for intermittently feeding an adhesive tape over a bed-plate on which the pieces to be joined are placed, together with means for cutting off the tape and pressing the severed piece against the pieces of the stay, to join the same.

20 In the machine of my said prior patent, difficulty was frequently encountered, when use of the machine was discontinued for a short time, from the fact that the tape, which is moistened as it is drawn into the machine, frequently adhered to the parts thereof, so that, when the machine was again started, it would not operate to feed the tape. The machine of my said prior patent was not adapted to be operated by 25 foot power, and for various reasons a foot-power machine for this purpose is desirable.

Other objects of the present invention are to provide means whereby the moistened tape may be prevented from adhering to 30 the machine to such extent as to cause difficulty in feeding after the machine has been idle for a space of time, and, further, to provide improved means for holding the tape against retraction while the feeding device is being moved to a retracted position; to provide means whereby the length of the piece of tape which is severed may be readily and accurately varied; to provide means whereby a machine of this character may be 35 easily operated by foot-power, and to improve my said prior machine in various particulars, as will hereinafter appear.

I accomplish these objects by the means shown in the accompanying drawings, in 40 which:—

Figure 1 is a side elevation of the machine made according to my invention, Fig. 2 is a central sectional view on the line $a-a$ of Fig. 3. Fig. 3 is a front elevation of the 45 machine, Figs. 4 and 5 are detail front and

side views of the feeding device, Fig. 6 is a horizontal section on the line $b-b$ of Fig. 1, and Figs. 7 to 10 are enlarged detail views of the tape-holding means.

As shown in the drawing, the machine 60 comprises a base 1, having two pairs of vertical rods 2 mounted thereon, and connected at their upper ends by suitable brace-bar 3, forming a frame. A carrier 4 is mounted to slide vertically on the two front rods, 65 2, 2, and said carrier is provided with a presser-head 5, which depends from the front side thereof. Said carrier 4 is connected to said frame by a vertically-disposed toggle comprising a pair of links 6 70 and 7, connected by a knuckle 8, and a horizontally-disposed toggle comprising a pair of links 9 and 10 connected by a knuckle 11. A treadle-rod 12 is pivoted to the knuckle 11, and a suitable return spring (not shown) 75 is provided, which normally acts to hold said treadle-rod 12 in raised position. With the double toggle arrangement above described it will be apparent that when a down-pull is exerted on the rod 12, both 80 toggles will be straightened, moving the carrier 4 downwardly, a strong leverage being provided, so that a light pull on the rod 12 will cause the carrier 4 to be forced down with ample pressure for the purpose. 85

As shown in Fig. 1, an adhesive tape 13 is mounted on a reel 14, in the rear of the machine, and is fed forwardly over a moistening-roll 15 and over the stationary shear-blade 16, on the bed of the machine, which 90 co-operates with a shear-blade 17 on the presser-head 5, as in my said prior machine. A depending bar 18 is connected, at its upper end, by a pivot 19 to the frame, and, at its lower end, is provided with a 95 horizontally-disposed support 20, over which the tape 13 is fed. A gripping-dog 21 is pivoted on said bar 18, said dog having teeth which are normally held, by a spring 22, in engagement with the strip 13, so as to 100 press said strip against an inclined face on the support 20, whereby, as the bar 18 is swung forwardly, the strip will be drawn from the reel and pushed over the shear-blade 16, said dog becoming disengaged 105 from the tape on the return movement, as described in my said prior patent.

A horizontally-disposed rod 23 is pivotally connected to the lower end portion of bar 18, said rod extending loosely 110

through a bracket 24 on the bed, and a spring 25 is mounted on the rod 23 between said bracket 24 and a collar 26 on the rod.

A nut 27 is threaded on the extreme end 5 of the rod, said nut being adapted to engage bracket 24 when said rod is drawn forward to act as an adjustable stop to limit the forward swinging of the bar 18 and thus vary the length of the piece to be severed, the 10 length of the piece which will be severed being indicated by the position of the nut 27 on a scale 24.

A cam 28 is mounted on the carrier 4, and a roll 29 is rotatably mounted on the 15 bar 18 in position to engage said cam, said spring 25 acting constantly to hold the rod against said cam in all vertical positions of the carrier. The upper portion of the cam 28 is inclined so that it extends upwardly 20 and forwardly, and is so arranged that when the carrier is lowered, the bar 18 will be permitted to swing forwardly. Said cam is also provided with a recess 28' in the higher portion thereof, into which the roll 25 29 is adapted to move when the carrier is in its highest or normal position.

A work-supporting bed is provided directly beneath the head 5, which consists of a rubber block 30 set in a recess formed in 30 the table of the machine.

In the power-driven device of my said former patent I found it necessary to employ a yielding pressing member to enable the reciprocating presser or plunger to press 35 the severed piece against the stay piece for a sufficient length of time to cause the tape to adhere to the stay-pieces. However, with the treadle-operating machine herein-described the presser-head may be held in 40 engagement with the work as long as is necessary, so that it is only necessary to provide a slightly resilient bed, adapted to yield sufficiently, when pieces of unequal thickness are connected, to permit pressure 45 to be applied to both pieces. In this connection it may be noted that the divided metal plate of my said prior machine is only effective, in permitting approximately equal pressure on pieces of unequal thickness, 50 when the abutting ends thereof are held over the line of division of said plates, and, as operators frequently fail to do this, the purpose of the machine in this regard is practically defeated. With the form of 55 bed herein shown, however, the accurate positioning of the pieces beneath the presser-head is unnecessary.

A foot 32 is mounted to reciprocate vertically in a bracket 33, mounted on the table 60 of the machine, said bracket being provided with a spring-pressed friction-plate 34, which is adapted to hold said foot 32 in any vertical position to which it may be moved.

A bracket 35 is mounted on the carrier 4, 65 and a rod 36 is connected to said foot 32

and extends through said bracket into a chainber 4' in the carrier, said rod having a spring-buffer 37 at its lower end, which rests on the upper end of the foot 32, and a head 38 at its upper end, which retains a 70 spring-buffer 39.

A pair of vertically-projecting fingers 40 are mounted on the bed, directly in the rear of the shear-blade 16, said fingers terminating slightly below the level thereof, and the lower end of said foot 32 is provided with a projecting toe 32', which is disposed to press the tape against the ends of said fingers 40 when moved downward.

A holding-plate 41, having teeth 41' at 80 its front end, is adjustably mounted on the bed in the rear of the fingers 40, said teeth being slightly upturned and beveled on their under sides, so that when the tape is pressed down on said fingers 40, by said toe-portion 32', said teeth will be caused to pierce the tape to a slight extent.

The operation of the above-described device is as follows: The bar 12 is drawn downwardly by a treadle, depressing the 90 carrier 4, as described above, and, as said carrier is moved downwardly, the inclined portion of the cam 28 will be carried opposite the roll 29, so that the spring 25 is permitted to swing the bar forwardly. The 95 foot 32 will at that time be in raised position, and the gripping-dog 21, on the lower end of the bar 18, will draw the tape 13 from the reel 14, over the moistening-roll 15, and push the end-portion thereof, assuming that the tape has been severed by the shear in the previous operation, beneath said foot, over the shear-blade 16, into position over the stay-pieces which have previously been placed on the bed 30. As the 100 carrier 4 descends, the shear-blade 17 will sever a portion of the tape of sufficient length to extend across the pieces to be connected, and the head 5 will press said severed portion against said pieces, so that the 110 tape will be caused to adhere firmly thereto.

As the carrier descends, the bracket 35 will engage the upper end of the foot 32, through the medium of the spring-buffer 37, so that the tape will be firmly clamped 115 against the fingers 40, the spring 37 being adapted to yield to a sufficient extent to compensate for any variations in thickness of the pieces to be connected, or for inaccuracies of adjustment. When the carrier 4 is again raised, the friction-plate 34 will hold the foot 32 in a depressed position during the greater portion of the lifting movement of the carrier, during which time the tape will be firmly clamped against the bed. 120 As the carrier is lifted, the cam 28 will push back the swinging-bar 18, so that the gripping-dog 21 will ride over the tape, as it is held from being drawn back by the toe 32'. The parts are so timed that, when the 125 130

higher end of the inclined portion of the cam 28 engages the roll 29, so that the bar 18 is swung rearwardly to its full extent, the bracket 35 will engage the spring 39 and draw the foot 32 upwardly out of engagement with the tape. At the end of the upward movement of the carrier, the depressed portion 28' of the cam will be opposite the roll 29, so that the spring 25 will force said roll into said recess 28' and thus swing forward the bar 18, causing a slight forward feeding of the tape, the purpose of which is as follows: If the tape, after having been pressed firmly against the fingers 40 by the foot 32, were permitted to remain in that position for an appreciable length of time, it would adhere to the bed, so that, when the next operation was performed, the feeding means would be prevented from pushing the tape forwardly, but, as the slight forward feeding movement, above referred to, takes place at the end of the operation, the portion of the tape which was pressed against the fingers 40 will be moved out of engagement therewith before it has time to adhere, so that it will then rest lightly on the edge of the shear-blade 16 and will not adhere thereto, even if permitted to remain in this position until the cement thereon becomes dry. As the area of the surface at the ends of the fingers 40 is small, there is but slight possibility that the tape will adhere thereto to an appreciable extent before the slight feeding motion, above described, takes place. As the plate 41 is so adjusted that its teeth will pierce the tape to a slight extent, when the foot 32 presses the latter against the bed, if the foot should not securely hold the tape, or if the foot should be moved out of engagement with the tape before the rearward swinging movement of the bar 18 was finished, said teeth would prevent the tape from being drawn back by the gripping-dog 21, thereby obviating the possibility of irregular feeding of the tape.

It will be apparent that the distance which the tape is fed on each reciprocation of the carrier, and, therefore, the length of the severed piece may be readily varied by merely adjusting the nut 27, and the position to which it should be adjusted for stays of different widths may be readily determined by its position with relation to the scale 24'.

I claim:

1. In a stay-joining machine, means for severing and pressing a piece of adhesive tape against the work, means for intermittently feeding the tape to said severing and pressing means, comprising a gripping device, adapted to engage the tape to feed the same when moved in one direction, holding means for engaging the tape during the reTRACTING movement of said gripping device,

means for releasing said holding means from the tape at the end of said movement, and means for thereafter moving said gripping device to free the tape from said holding means, substantially as described. 70

2. In a stay-joining machine, means for severing and pressing a piece of adhesive tape against the work, means for intermittently feeding the tape to said severing and pressing means, comprising a gripping device adapted to engage the tape to feed the same when moved in one direction, means for holding the tape during the retracting movement of said gripping device, and means for slightly advancing the tape after the feeding operation has been finished to free the same from said holding means, substantially as described. 75

3. In a stay-joining machine, a work-supporting member and a pressing member movable to and from the same, a gripping device movable to and from said members to feed an adhesive tape thereto and adapted to grip the tape on its feeding movement and to become disengaged therefrom on its retracting movement, a clamping device for holding the tape during said retracting movement and adapted to be released therefrom at the end of said movement, and means for advancing the gripping device to feed the tape a short distance during the latter portion of the retracting movement of said pressing member, substantially as described. 80

4. In a stay-joining machine, having a work-supporting member and a pressing member movable to and from the same, a gripping device movable to and from said members to feed an adhesive tape thereto and adapted to grip the tape on its feeding movement and to become disengaged therefrom on its retracting movement, a clamping device for holding the tape during said retracting movement and adapted to be released therefrom at the end of said movement, a spring normally acting to move said gripping device to perform the feeding operation, means, actuated by said pressing member as it is moved to its retracted position, for retracting said gripping device against the action of said spring and for permitting the spring slightly to advance said gripping device during the latter portion of the retracting movement of said pressing member, substantially as described. 100

5. In a stay-joining machine having a work-supporting member and a pressing member reciprocally movable to and from the same, means for intermittently feeding a tape to said members, comprising a gripping device adapted to engage the tape to feed the same as the pressing member is moved toward the supporting member, and to be disengaged from the tape on the reTRACTING movement of said pressing member, 105

4
a tape-clamping device supported independently of said pressing member and movable thereby to engage the tape at the end of the feeding movement thereof, means for holding said clamping device in engaging position during the first portion of the retracting movement of said pressing member, and means, actuated by said pressing member, during the latter portion of said retracting movement, for moving said clamping device to disengage the tape, substantially as described.

5 6. A stay-joining machine having, in combination, means for pressing a severed piece 15 of adhesive tape against the work, mechanism to feed the adhesive tape, means to sever said piece from said tape prior to the pressing operation, and means for imparting to said tape a slight forward movement 20 after the severing operation and prior to the succeeding feeding movement.

7. A stay-joining machine having, in combination, means for pressing a severed piece 25 of adhesive tape against the work, means for severing said piece, mechanism for feeding the adhesive tape prior to the severing operation, and means acting through said feeding mechanism for imparting to said tape a slight movement to disengage the 30 tape from said severing means prior to the succeeding feeding movement.

8. A stay-joining machine having, in combination, means for pressing a severed piece 35 of adhesive tape against the work, means including a stationary and a movable member for severing said tape with the adhesive surface of the tape in contact with the stationary member, mechanism for feeding said tape a predetermined distance between the

severing operations, and means for moving 40 said tape slightly with respect to said stationary severing member after the movable severing member has been moved away from the stationary member and before the next feeding movement is started.

9. A stay-joining machine having, in combination, means for pressing a severed piece 45 of adhesive tape against the work, means including a stationary and a movable member for severing said tape with the adhesive surface of said tape in contact with the stationary member, mechanism for feeding said tape a predetermined distance between the 50 severing operations, and means acting through said feed mechanism for moving 55 said tape slightly with respect to said stationary severing member after the movable severing member has been moved away from the stationary member and before the next feeding movement is started.

10. A stay-joining machine having, in combination, means for severing a piece of tape, means for pressing the severed piece against the work, tape feeding mechanism, tape disengaging mechanism, a treadle controlled 60 member, and means actuated by movement of said member in one direction for operating said feeding mechanism and by movement of said member in the opposite direction for operating said disengaging mechanism.

In testimony whereof, I have signed my name to this specification, in the presence of two subscribing witnesses.

FREDERICK L. ANDERSON.
